UNITED STATES PATENT OFFICE.

KARL L. LANDGREBE, OF BETHLEHEM, PENNSYLVANIA.

METALLIC RAILWAY-TIE.

No. 920,161.

Specification of Letters Patent.

Patented May 4, 1909.

Application filed December 26, 1908. Serial No. 469,206.

To all whom it may concern:

Be it known that I, KARL L. LANDGREBE, a citizen of the United States, residing at Bethlehem, in the county of Northampton and State of Pennsylvania, have invented a new and useful Improvement in Metallic Railway-Ties, of which the following is a specification, reference being had therein to the accompanying drawings.

10 This invention relates to certain new and useful improvements in metallic railway ties; and the primary object of the invention is to provide a simple, strong, light and inexpensive tie to which one or more rails can be easily and securely fastened.

15 My invention aims to provide a metallic tie of a form that can be readily made in steel or other desired metals and to which rails can be fastened in the usual well known simple manner.

20 A further object of my invention is to provide a metallic tie adapted to receive and firmly hold a stool or support constructed of wood or a like material for supporting and 25 fastening the rail. By this combined construction I obtain a high degree of resiliency, strength and superior lasting quality of the tie.

20 The invention also consists in compressing or compacting the stool block thus rendering the said blocks more dense and greatly increasing the holding power of the spikes.

30 I prefer to use wooden stool blocks treated with some wood preservative, such as sulfate of zinc which will render the blocks practically indestructible except by mechanical forces.

35 In the accompanying drawings Figure 1 is a plan view of the preferred form of my improved tie. Fig. 2 is a longitudinal section through line 2—2 of Fig. 1. Fig. 3 a section on line 3—3 of Fig. 2. Fig. 4 is a section on line 4—4 of Fig. 2. Fig. 5 is a broken enlarged perspective view of my preferred form 40 of tie.

45 My improved tie A, is cast from steel or other metal, and is preferably made integral that is of one continuous piece, and comprises a base plate B top plate C between which is an open space D. From the base plate B separated at a distance from one another equal to the space between the track rails are box tie receptacles H bounded by side walls F—F and end walls E and G the 50 side walls F tapering toward the ends of the

tie in vertical walls f—f to insure stiffness and rigidity to the said walls F—F. Stool blocks I—I for support of the rails T—T are fitted and held firmly in the said box like receptacles H by means of spikes or bolts K which enter through the openings h in the side walls F. Drainage holes n are provided at the bottom plate B forming the lower portion of the receptacles H. The sides of the plates B and C are preferably provided with a slight bead b thus strengthening the material at this portion where it is most subject to blows and shocks. The stool blocks are preferably made up of several sections as shown in Fig. 3 as cheaper as well as sounder 60 and stronger material can thus be obtained. The rails are secured to the stool blocks by means of any desired form of spike or other holding means S.

55 This tie when set with its base upon the road bed offers an ample surface for contact with the ballast to hold it firmly in place, tamping of the ballast being readily accomplished underneath the plate B, in the opening D, and at the ends E. The rail being 80 bolted upon the yieldable blocks I, the vibration resulting from the passage of train is absorbed thereby, this being aided by the peculiar open arrangement D, provided by the plates B and C. Furthermore it will be 85 evident that by the use of a minimum amount of material a maximum strength is secured, insuring economy in the manufacture and transportation and laying of the ties.

90 It will be evident from an inspection of the drawing that I provide a tie wherein great stiffness is obtained in a horizontal plane, and resiliency is retained in the vertical plane, the binding plates B and C lying in a 95 horizontal plane and being of a comparatively thin vertical section, and thus exceedingly resilient and flexible, allowing of vertical motion for adjustment of the tie in respect to the road bed as the weight of traffic passes 100 over the rail.

Having thus described my invention, I claim as new and desire to secure by Letters Patent—

1. A metallic tie comprising separated 105 horizontally disposed base and top plates provided with box-like receptacles located at either end thereof, the said receptacles being integrally formed with the said base and top plates which plates are otherwise 110

not connected one with the other, whereby vertical resiliency of the tie is obtained, as and for the purpose specified.

2. A metallic tie comprising a horizontally disposed base plate provided with box-like receptacles at either end of the same, a top plate integrally formed with the inner end walls defining the said receptacles, the said top and bottom plates being integrally connected one with the other solely by means of the end walls of the said receptacles whereby vertical resiliency of the tie is obtained, as shown and described.

3. The combination with a metallic tie comprising horizontally disposed separate base and top plates, box-like receptacles at either end of said plates integrally formed therewith, the said base and top plates being connected with each other solely by means of the inner end walls of the aforesaid receptacles whereby a resilient and flexible tie is obtained.

4. The combination with a metallic tie comprising horizontally disposed separate base and top plates, box-like receptacles at either end of said plates integrally formed

therewith, the said base and top plates being integrally connected with each other solely by means of the inner end walls of the aforesaid receptacles and yieldable blocks secured within the latter, whereby a resilient and vertically flexible construction of tie is obtained, as and for the purpose specified.

5. The combination with a metallic tie comprising horizontally disposed separate base and top plates, box-like receptacles at either end of the said plates integrally formed therewith, the said plates being separated or not in contact with each other throughout their central portion but being integrally connected with each other solely by means of the inner end walls of the aforesaid receptacle whereby a resilient and flexible construction of tie is obtained.

In testimony whereof, I have signed my name to this specification in the presence of two subscribing witnesses.

KARL L. LANDGREBE.
